UNITED STATES PATENT OFFICE.

GUSTAV EGLOFF, OF CHICAGO, ILLINOIS, AND ROBERT T. POLLOCK, OF NEW YORK, N. Y., ASSIGNORS TO UNIVERSAL OIL PRODUCTS COMPANY, OF CHICAGO, ILLINOIS, A CORPORATION OF SOUTH DAKOTA.

PROCESS OF TREATING HYDROCARBON OILS.

Application filed December 9, 1920, Serial No. 429,337. Renewed February 5, 1927.

Our invention relates to a process of treating petroleum oil, consisting in distilling relatively heavy hydrocarbon oils of asphaltic base or under an emulsified condition by 5 means of surface distillation in vacuum for the purpose of separating the hydrocarbon fractions therefrom with a minimum amount of decomposition so as to recover lubricating oil fractions therefrom as they occur in the 10 oil naturally, and to cut to a minimum the amount of sulphuric acid necessary in refining of lubricating oils for industrial uses.

Our process and apparatus covers the surface distillation of hydrocarbon oils by 15 means of utilizing an electrically heated plate, or series of resistance bars, so that the heat therefrom distills the surface layers of said hydrocarbons while under vacuum for instance in excess of 10 inches. In the ordinary refinery practice the method of preventing destructive distillation of heavy hydrocarbon oils is to constantly inject large 20 volumes of steam into the body of the oil to prevent the direct firing from decomposition of the heavy hydrocarbon oils. It has also been found that when distilling heavy hydrocarbon oils under vacuum, such as emulsified oils or heavy asphaltic oils; in the former case it is practically impossible to 25 apply heat to the bottom of the still and put a vacuum upon same without "puking" the still content, and also in the latter case, to prevent destructive distillation of heavy hydrocarbon oils by means of direct fire upon 30 the bottom of the still.

By our process we have found that we can 35 vacuum distill the emulsified oils, or heavy hydrocarbon oils, such as asphaltic, by means of surface heating with an electrically heated resistance plate set upon the surface of the oil to be distilled, and that we can control the rate of distillation to a nicety with the minimum of decomposition practically obtainable.

45 Fig. 1 is a longitudinal cross section of our apparatus, Fig. 2 is a cross sectional view of the still, 1 representing a vacuum still supported upon concrete piers 2. 3 is a man-hole plate attached to the still 1, said still 50 having pressure gauge 4. A raw oil charging pump 5 is connected to a storage tank (not shown) by means of pipe 6 having control valve 7 positioned therein. The discharge side of pump 5, is connected to pipe

8, having control valve 9 positioned therein. 55 10 is an electric resistance material plate set in the body of the still, connected with fittings 11 and wires 12, connected with electric generator 13. 14 is a vapor line connection to water condenser coil 15 set within 60 condenser box 16. A receiver for oil 17 is connected to water condenser coil 15. A pressure gauge 18 is positioned on top of receiver 17, and upon said receiver is attached a gauge glass 19. 20 is a draw-off pipe for 65 liquid condensate, having control valve 21. Valve 22 is a pressure control valve connected with vacuum 23, which is capable of drawing a vacuum as high as 28 inches.

Fig. 2 is a cross sectional view of the still 70 1, having heating element plate 10 set therein. Still 1 is charged by means of raw oil pump 5 to level with the heating element 10, said level being maintained by the charging pump 5. When this liquid level in still 1 75 has been reached, vacuum pump 23 is started and the generator 13 is operated so that the electrical energy flow therefrom is converted into heat by means of resistance material 10 set within the still. The temperature of distillation is so maintained, and vacuum also 80 maintained, that the rate of distillation is of that character that foaming or "puking" of the still content, where an emulsified oil is subjected to distillation, is impossible. 85

We have found our process to act excellently with oils of a highly emulsified character of a gravity not lighter than 20 degs. Baumé, such as Casmalia crude, Panuco crude, and certain kinds of Santa Maria 90 crudes. Our process gives a minimum of radiating losses and smoothly distills the oil with a high capacity per unit, with a minimum of destruction of the hydrocarbons, as they are in the hydrocarbon oil to be treated, 95 and with a minimum of further refining, such as sulphuric acid treatment or caustic soda wash, or fuller's earth, or bone black filtration.

We claim as our invention : 100

1. A process of treating petroleum oil, consisting in distilling relatively heavy asphaltic and emulsified oils, of a gravity not lighter than 20° Baumé, applying heat to the oil at the upper surface of the oil body 105 by means of an electrically heated element extending above the body of the oil and throughout the still, and during distillation

subjecting the oil to a vacuum action in excess of ten inches.

2. A process of treating petroleum oils, consisting in distilling relatively heavy asphaltic and emulsified oils, applying heat to the oil at the upper surface of the oil body by means of an electrically heated element extending above the body of the oil, and subjecting the oil to a vacuum action during distillation.

3. A process for treating petroleum oils, consisting in distilling the oils by applying heat to the oil at the upper surface of a body of the oil by means of an electrically heated element extending above the level of the body of the oil, and subjecting the oil to a vacuum action during the distillation.
